UNITED STATES PATENT OFFICE

WILLIAM J. HALL, OF DETROIT, MICHIGAN, ASSIGNOR, BY MESNE ASSIGNMENTS, OF THIRTY PER CENT TO OLLIE L. HERRON, THIRTY PER CENT TO JOSEPH B. ZIMMERS, THIRTY-THREE PER CENT TO WILLIAM J. HALL, AND SEVEN PER CENT TO R. C. SCHEMMEL

HOOD CONSTRUCTION

Application filed April 29, 1932. Serial No. 608,282.

The invention relates to hood constructions and it has particular relation to the manner of hinging parts of the hood together and to a vehicle body.

5 In certain respects the invention relates to that disclosed in my prior applications for patents on hood constructions, Serial No. 588,566 filed January 25, 1932, and Serial No. 602,516 filed April 1, 1932.

10 Similarly to the application for patent last filed, one object of the present invention is to provide a hood construction in which the wings of the hood are hinged directly together by coacting rolled edges and 15 hinged to the radiator and the cowl of a vehicle without necessitating the use of a supporting pivot connecting such parts of the vehicle.

Another object of the invention is to provide 20 a hood construction in which the wings of the hood are hinged together and to the radiator and cowl of the vehicle, directly by rolled edge portions of the wings without requiring the use of any separate pintles, 25 pins or the like.

Another object of the invention is to provide 30 a hinge construction for a pair of plates or the like, in which a rolled edge portion of one of the plates constituting a part of a rolled edge hinge connecting them, may be employed directly as a pintle or pivot portion for pivoting the plates on a stationary support.

Another object of the invention is to provide 35 an improved hinge construction for hoods, of this general character, which is so constructed that the outwardly exposed and finished surfaces of the hood in the region of the hinge will not be marred, scratched or 40 otherwise injured during any opening or closing movement of the hood wings, and which has a smooth and efficient manner of operation throughout such opening and closing movements.

45 Another object of the invention is to provide an improved hood wing hinge, which has desirable flexibility to the end that undesirable strains will not be imposed upon the pivotal connection between the wings, 50 hood and vehicle in closing or opening of

either wing thereof, so that the hinge will be extremely durable and resistant to strains such as usually caused during final opening movement of either wing when considerable momentum force is imparted to the hinge 55 connection.

Other objects of the invention will be apparent from the following description, the drawing relating thereto and the claims hereinafter set forth.

60 For a better understanding of the invention reference may be had to the accompanying drawing forming a part of the specification, in which:

Figure 1 is a fragmentary plan view of a 65 vehicle having a hood construction designed according to one form of the invention;

Figure 2 is a cross-sectional view on a larger scale, taken substantially along the line 2-2 of Figure 1;

70 Figure 3 is a fragmentary plan view of the construction illustrated by Figure 2, particularly illustrating the manner of pivoting the hood on the radiator or cowl of the vehicle;

75 Figure 4 is a cross-sectional view on a larger scale taken substantially along the line 4-4 of Figure 2;

Figure 5 is a perspective, end view of the hood, particularly illustrating the hinge 80 connection between the hood wings, as seen when the hood is removed from the vehicle; and

Figure 6 is an end view on a larger scale, 85 as seen substantially along the line 6-6 of Figure 5.

Referring to Figure 1, a motor vehicle is illustrated at 10, the radiator thereof at 11 and the cowl at 12. The hood is indicated at 13 and comprises oppositely disposed wings 14 and 15 hinged together at their meeting edges as indicated at 16. Generally in conventional constructions, the hood wings are pivoted on a long pin or pintle connected at opposite ends to the radiator and cowl, and the present invention particularly is concerned with the manner of hinging the wings together and to the radiator and cowl in an improved manner.

Referring now particularly to Figures 5 100

and 6, the hood wing 15 is illustrated as having an inwardly turned flange 17 and the wing 14 similarly as having an inturned flange 18, such flanges being shown as spaced 5 and substantially parallel when the wings are in closed position. The flange 17 is rigidly connected as by welding, for example, to a similar flange 20 on a male hinge element 21 formed by rolling an edge of the 10 element in the manner shown. The flange 18 on the hood wing 14 similarly is connected to the flange 22 of a female hinge element 23 adapted to cooperate with the male member 21. It of course should be understood that 15 the edges of the wings 14 and 15 may be rolled to provide the male and female hinge elements respectively, without manufacturing such elements separately and then welding them to the wings, but ordinarily the first 20 described manner of manufacturing will facilitate the metal rolling operations. The particular construction of the male and female hinge elements has been illustrated and described in my copending applications for 25 patent above identified, and accordingly, it does not seem necessary to explain them herein in detail. It may be added that in many instances the male and female elements may constitute an article of manufacture, to be 30 subsequently connected to hood wings by the purchaser.

When the parts are associated as shown in Figure 6, it is apparent that the male and female members are so related that further 35 closing movement of either hood wing is resisted. In opening either wing, as for example the wing 15 as shown in broken lines, the hook portion of the male hinge element, indicated at 24, finally hooks over the end 40 edge of the female element, indicated at 25', to provide a limit or stop to the opening movement. Of course, if the wing 14 is opened, the male and female members will move relatively in the same manner as when opening 45 the wing 15, although in the one case, the male element will move while the female element will remain stationary, while in the other case the male element will remain stationary and the female element will move. 50 The male and female elements are associated by longitudinally telescoping them and it will be appreciated that the construction as shown simulates the ordinary hood hinge wherein 55 a long pintle or pin is employed, without necessitating use of the latter. It is apparent that the male and female members are continuous from the cowl to the radiator and hence that water or other matter may not leak into the space below the hood through 60 the hinge. The flanges 17 and 20 on the wing 15 and the flanges 18 and 22 on the wing 14, being positively connected together, will prevent the ingress of any water or the like into the motor space although, as stated previously, 65 the male and female elements may be in-

tegral with the wings so as to completely eliminate any possibility of seepage of water or the like between the flanges on either wing.

For pivoting the wings on the radiator and cowl, the male element 21 extends beyond opposite ends of the hood as shown by Fig. 5, and such projecting ends, as also illustrated in Figure 4, preferably constitute a portion of the male element, in which the flange 20 and a curved part of the element, are removed 70 substantially to the line 25. While such projecting ends of the male member may not constitute an arcuate element having a single radius of curvature, they may be satisfactorily pivoted in journals 27 mounted on 75 the radiator and cowl. It would, of course, be possible to have the projecting ends of the male element provided with truly cylindrical surfaces so as to smoothly fit in the journals 27 but normally this would not be necessary as satisfactory pivotal action may be obtained without doing this, and it is much easier to use the projecting ends of the male element without altering their curvature, as 80 to make such alterations would introduce 85 other manufacturing steps and increase the expense of manufacture. The journals 27 have flanges 28 and 29 fitting under portions 30 and 31 of the cowl and radiator and such flanges are secured in position by means of 90 bolts 32. Normally, the hood wings 14 and 15 have their side edges resting on such portions 30 and 31 of the radiator and cowl and this arrangement still further stabilizes the 95 position of the ends of the male element in the journals 27.

In opening the hood wing 15, for example, it is apparent that the male element will move with the wing and hence pivot in the journals 27 and that finally when the wing reaches its open position, the hook portion 24 of the element will engage the end edge 25' of the female element to hold and lock the wing in open position. If the hood wing 14 is opened, the male element will remain substantially stationary and hence any substantial pivotal movement of its projecting ends in the journals 27 will not be necessary. In a construction of this character, attention is directed to the fact that a considerable manual and momentum force may be exerted through a wing when it is thrown into its open position owing to the moment arm through which the force is imparted by the hand moving the side edge of the wing and this force naturally tends to forcefully continue movement of the hood wing past its intended open position. For example, in opening the wing 15, there is a considerable force tending to move the wing past its intended, open position in which the hook 24 on the male element initially engages the end edge 25' on the female element. In the ordinary hood in which a pintle is used, this force has a very undesirable result in that 110 115 120 125 130

- eventually and ordinarily in a short time, parts of the hinge connection between the wings and between the wings and the cowl the radiator become broken. In the present construction, after the wing 15 reaches the intended final open position, the momentum force of the wing will be dissipated through the give and resiliency of the hinge elements and largely through the female element and adjacent portions of the wing 14. If the wing 14 is opened, this force tending to move it past its final open position, is resiliently dissipated largely through the male element and the adjacent parts of the wing 15. Moreover, this momentum force does not act appreciably, if at all, on the journals 27 and the male element portions therein except to rotate them, but to the contrary is dissipated mainly through the opposite wing and there is very little tendency to impart any force to the journals or the male elements therein to loosen the journal connections on the radiator and cowl. This may be illustrated perhaps a little more clearly by using the arrow A in Figure 6. In opening the wing 15, when the latter tends to move past its supposed limited open position, the momentum force, instead of acting on the journals 27, merely tends to slightly move the female element and parts of the wing 14, downwardly into the motor space in the direction generally indicated by such letter A. Of course, this movement is slight and practically unnoticeable, but nevertheless it is extremely advantageous in that it cushions the force and prevents the imparting of undesirable forces to the journals 27, as well as to the rolled portions of the hinge.
- A hood of the type described may be manufactured very inexpensively because it is only necessary to roll the male and female members from edges of elongate and flat plates and then fasten such elements to the wings, or else roll such edges directly into edge portions of the wings without manufacturing them separately of the latter. The use of pintles or pins of any character is avoided and it is only necessary to manufacture the wings and then pivot them on the radiator and cowl by means of projecting ends of the male element. The hinged construction thus provided is water tight and, moreover, its appearance is especially pleasing in that it simulates the ordinary type of hinge to which the public has become accustomed. Moreover, as stated in my prior copending applications for patent, the hinge is so constructed that surfaces exposed to view on the wings of the hood will not be marred or scratched during any movement of the wings to their open or closed positions.
- Although only one form of the invention has been described and illustrated in detail, it will be apparent to those skilled in the art that various modifications may be made without departing from the scope of the appended claims.
- I claim:
1. A hood construction comprising a pair of wings having complementary rolled edge portions for hinging them together and means for pivotally mounting opposite ends of the wings on spaced parts of a vehicle, said means comprising projecting end portions of one of the rolled edges. 70
  2. A hood construction comprising a pair of wings having complementary rolled edge portions for hinging them together, and means for pivotally mounting opposite ends of the wings on spaced parts of a vehicle, comprising projecting end portions of one of the rolled edges, said rolled edges constituting the sole hinging connection between the wings. 75
  3. In combination, a pair of sheet elements having rolled edges directly coacting with each other to form a hinge for hingedly supporting one element on the other, and means at opposite ends of the rolled edges for pivotally supporting the elements on spaced stationary supports, said means comprising projecting ends of one of the rolled edges, at opposite ends of the hinge. 80
  4. In combination, a pair of sheet elements having rolled edges directly coacting to provide a hinge connecting them, and means at one end of the hinge for hingedly supporting the elements on a stationary support, said means comprising a projecting end of one of the hinge elements to be pivotally supported in a journal on the support. 95
  5. In combination, a pair of sheet elements having rolled edges directly coacting to provide a hinge connecting the elements, one of such rolled edges projecting beyond the end of the hinge for pivotally supporting it and the elements on a stationary support, and means for limiting hinging action of either element in one direction. 100
  6. A hood construction comprising a pair of wings having rolled edges directly coacting to form a hinge connecting the elements, the inner of said rolled edges projecting beyond one end of the hinge for pivotal mounting in a journal on a stationary support. 110
  7. In combination, a stationary support having a journal bearing, a pair of sheet elements having rolled edges coacting to form a hinge connecting them, one of said edges projecting beyond the end of the other, and pivotally into the journal bearing on the support. 115
  8. In combination, a stationary support having a journal bearing, a pair of sheet elements having rolled edges coacting to form a hinge connecting them, one of said edges projecting beyond the end of the other and into the journal bearing on the support, the curved surface of such journal corresponding generally to the curvature of the curved sur- 120
  - 65 125
  - 65 130

face of the hinge element projecting thereinto to permit pivotal movement of the latter in such journal.

9. In combination, a stationary support having a journal bearing, and a pair of sheet elements having rolled edges coacting to form a hinge connecting them, the inner of such rolled edges projecting beyond the end of the hinge and into the journal to provide 13 a pivotal support for the hinge and sheet elements.

10. In combination, a vehicle having a cowl and radiator, journals on the cowl and radiator, and hood wings having rolled edges directly coacting to hinge them together, one of such rolled edges projecting at its ends, into and being pivotal in the journals for pivoting the hood on the vehicle.

11. A hinge comprising a pair of hinge 20 parts each having a bead formed therein for interfitting pivotal engagement, the bead of one of said hinge parts projecting beyond the other, and a bracket member mounted on a fixed support in which said projection is journaled.

12. A hood hinge comprising a pair of hinge parts each having a bead formed therein in one edge for interfitting pivotal engagement, the bead of one of said hinge parts projecting beyond the other to form a trunnion, and a bracket member mounted on a fixed support in which said trunnion is journaled.

13. In a hood hinge, an outer hinge part having a bead formed in one edge thereof, an inner hinge part having a bead formed in one edge thereof for interfitting pivotal engagement with the bead of the outer hinge part, fixed brackets located adjacent the ends of the hinge, the bead portion of one of said hinge parts at each end being shaped to form a bearing portion journaled respectively in said brackets.

14. A hinge for coupling independent and relatively movable body parts comprising a 45 pair of hinge members each having a bead formed in one edge for interfitting pivotal engagement, the opposite edge being connected to one of the body parts, a fixed bracket 50 provided with a journal recess, and an extension on the end of one of said hinge parts received in said journal recess.

15. A hinge for connecting a pair of hood sections having laterally extending flanges at their adjacent edges comprising, inner and 55 outer hinge parts in the form of elongated strips having beads formed in one edge thereof for interfitting pivotal engagement, the opposite edges of said hinge parts being secured to the flanges of said hood sections to 60 position the adjacent edges of said hood sections contiguous with the outer bead, and brackets in which the ends of said hinge are journaled.

16. A hinge for connecting a pair of hood 65 sections comprising a pair of hinge parts se-

cured to said hood sections and having beads formed therein for interfitting pivotal engagement, one of said beads being extended at each end to form trunnions, and brackets for receiving said trunnions, the adjacent portions of said hood sections being cut away to accommodate said brackets.

17. In combination, a vehicle having a cowl and radiator, journals on the cowl and radiator, hood wings having turned, interfitting edge parts directly coacting for hingedly connecting the wings, each end of the assembled hinge parts having one of the turned edges projecting beyond the end of the other edge part, and into the journals respectively, and means for locking portions of the hinge parts upon normal opening movement of either wing, so as to resiliently limit further opening movement by the resiliency of the parts around the axis of hinging movement.

18. In combination, a pair of spaced supports having journal openings, and sheet sections having turned and interfitting edges directly coacting to hinge them together, one of such edges projecting at its ends into and being pivotal in the journals for pivoting the sections on the supports.

19. In combination, a pair of spaced supports, a pair of hinge parts having turned, interfitting edge parts directly coacting for hingedly connecting them, each end of the assembled hinge parts having one of the turned edges projecting beyond the end of the other edge part and means for pivotally mounting said projecting ends on the supports.
